UNITED STATES PATENT OFFICE

114,057

DESIGN FOR AN IRONING MACHINE GEAR HEAD

John A. Castricone, Peoria, Ill.

Application November 17, 1938, Serial No. 81,169

Term of patent 14 years

To all whom it may concern:

Be it known that I, John A. Castricone, a citizen of the United States, residing at Peoria, in the county of Peoria and State of Illinois, have invented a new, original, and ornamental Design for an Ironing Machine Gear Head, of which the following is a specification, reference being had to the accompanying drawing, forming part thereof.

Fig. 1 is a side elevational view of an ironing

machine gear head showing my new design. The control handle of the ironing machine is shown in dotted outline.

Fig. 2 is a front elevational view thereof with a control handle shown in broken lines in Fig. 1, omitted.

I claim:

The ornamental design for an ironing machine gear head, as shown and described.

JOHN A. CASTRICONE.
